UNITED STATES PATENT OFFICE.

GEORGE M. WILLIAMS, OF ELIZABETH, NEW JERSEY, ASSIGNOR TO P. LORILLARD COMPANY, OF NEW YORK, N. Y., A CORPORATION OF NEW JERSEY.

SLIDE-BOX.

1,256,905.

Specification of Letters Patent. Patented Feb. 19, 1918.

Application filed May 11, 1917. Serial No. 167,943.

To all whom it may concern:

Be it known that I, GEORGE M. WILLIAMS, a citizen of the United States, residing at Elizabeth, in the county of Union and State 5 of New Jersey, have invented new and useful Improvements in Slide-Boxes, of which the following is a specification.

The present invention relates to improvements in containers formed of card-board 10 or other paper stock, pertaining more particularly to containers of the slide-box type adapted especially for carrying cigarettes or little cigars, although applicable for other uses.

Slide boxes of various types have been employed for the packaging of cigarettes, some forms carrying the cigarettes in a single row, other types employing a double row, the width of the box being controlled 20 by the particular type. Each type has its advantages and disadvantages, the single row type having the disadvantage of a considerable width of shell face supported only at its ends leaving a span practically free 25 from intermediate support excepting by the contents. Where a single row box is subjected to accidental pressure in the pocket, this pressure is necessarily applied to the cigarettes, tending to damage them. This 30 tendency is reduced in the double-row type—due to decrease in length of the span, but dependence must be placed entirely on the ability of the end walls of the slide and shell to resist such pressures, and where cigarettes 35 have been removed the difficulty is increased since the supporting effect of the contents is lost. Obviously, the advantage of the small span length is lost when any attempt is made to increase the number of cigarettes 40 in the package, since this involves increase in the span length.

While these difficulties have been present in connection with cigarettes having paper wrappers, they are greatly increased where 45 the boxes are employed in the packaging of "all-tobacco" cigarettes or "little cigars," especially where the cigars or cigarettes are of the low price type employing a more or less fragile wrapper. This difficulty has 50 practically necessitated the use of metal containers for this class of tobacco product.

The present invention is designed to meet these difficulties by employing one or more supports for the span, these supports being preferably formed integral with the slide or 55 slides and being of a type which will efficiently sustain the shell face or span against such pressures. This support preferably extends substantially throughout the length 60 of the shell and practically functions as a truss member or members between the opposite shell faces intermediate the ends of the shell span.

By this arrangement the length of the span is not limited by liability of damage 65 to the contents, so that a container of the desired capacity and of either single or double row-type may be employed. In practice it has been found that a container of this type will efficiently support the shell 70 where the contents are of the fragile wrapper type heretofore requiring the use of metallic containers, a result which makes it possible to employ the paper-board type 75 of container as a substitute for the metallic container for such use, thereby greatly decreasing the cost of containers, as well as permitting increase in size of the container with a resultant increase in capacity.

Another feature resulting from a container of the present type is the fact that although the shell may have a width greater than the length of the cigar or cigarette, the compartments formed by the support or supports have a width less than the length 85 of the cigar or cigarette so that shifting of the latter to a position parallel with the bottom of the slide, after a number of the 90 cigars or cigarettes have been removed, is prevented.

To these and other ends, therefore, my invention consists in the improved combination and arrangement of parts, together with the general arrangement of the slide blank, all as hereinafter more fully described, illustrated in the accompanying drawings, and more particularly pointed out in the appended claims.

In the accompanying drawings, in which similar reference characters indicate similar 100 parts in each of the views:—

Figure 1 is a perspective view of one

form of the container with the slide in nested position within the shell.

Fig. 2 is a similar view showing the slide as partially withdrawn.

Fig. 3 is a cross-sectional view.

Fig. 4 is a plan view of a blank adapted to form the slide.

Fig. 5 is a perspective view of a container for a single row of cigars or cigarettes, the slide being shown as partially withdrawn.

The shell 10 is of any preferred construction, being of a size adapted to receive the slide as is usual in this type of box.

The slide, indicated generally at 11, is arranged with one or more supports, indicated generically at 12, which extends substantially the full depth of the slide and which preferably have a length substantially equaling the length of the shell, although this latter may be varied as desired, the full length support being readily produced in blank form as indicated in Fig. 4, the support or supports serving to divide the interior of the slide into two or more compartments, each of which is adapted to receive cigars or cigarettes. As the support is of the full depth of the slide and practically presents an edge substantially double the thickness of the paper stock from which the slide is formed, each support will serve as a truss element for the shell spans provided by the width of the shell. And where the slide is formed from a single blank, thus producing the support as an integral part of the slide, the support becomes a substantially rigid partition for preventing inward or collapsing movement of the shell spans under pressure applied on the face or faces of the shell. Hence the shell, although made of paper stock, will not yield under pressure to an extent sufficient to provide damage to the contents even though the latter be of a character easily damaged by pressure.

As shown in Figs. 1, 2 and 5, the slide arrangement gives the general appearance of two slides of the usual type located side by side, and the present invention may be carried into effect by employing a pair of slides arranged side by side with the opposing walls of the two slides connected together in such manner as to tend to provide the rigid truss formation which is presented where the slide is formed from a single blank, and such double slide structure is intended to fall within the scope of the present invention.

However, it is preferred to form the slide from a single blank which may be of the form shown in Fig. 4 in which the body is shown as formed with two panels *a* connected by a web *b* which, when folded into a more or less bellows fold forms the support, each body panel having the usual slide-forming flaps and panels with the exception

that the side flaps of the loose panel *a'* are omitted, the adjacent half of the web *b* taking the place of the side flap of panel *a*. When the several flaps and panels are properly folded and the web given its bellows fold, the body panels *a* will be brought into proximity and will give the appearance of the two slides located side by side, the web, however, serving to connect the two slides and form the top of the support and at the same time divide the slide into compartments.

As shown more particularly in Fig. 3, the particular folding of the web and its connection with the panels *a* is such that when the slide is in position, the double thickness support provided by the web is more or less restrained against shifting at its edge by reason of the holding effect produced by the bringing of panels *a* in juxtaposition to each other, and the fact that the two plies of the support are located side by side and are held against relative movement at their free edges. A somewhat similar effect may be obtained by connecting opposing side flaps of two slides so as to produce this more or less rigidity to the double thickness structure; such results may be produced, for instance by adhesively connecting the opposing faces of such side flaps, an action which might be had in connection with the opposing faces of web *b* when folded, although such adhesive connection is not essential in the web formation, since the two-flap portions are held against relative movement by the web structure itself.

Any desired number of supports can be employed, the drawings showing but a single support, it being obvious, however, that an additional number of supports may be provided by forming the blank with additional panels *a* and employing additional web portions *b* between adjacent panels. As shown in Figs. 2 and 5, the invention may be employed in connection with boxes having the contents in single or in double rows.

Obviously, the invention will permit increase in the capacity of the boxes, since each compartment may contain a number of cigars or cigarettes equal in number to those contained in slide boxes of medium width, as for instance the type of package carrying two cigars in two rows of five each.

As indicated in Fig. 1, the revenue stamp may be applied over both cover flaps, thus preventing the opening of either flap without disrupting the stamp.

As will be understood, the general arrangement is such that the entire slide is moved bodily when the compartments are to be opened in the usual manner, due to the connection between the two panels.

While I have shown the support as extending a distance substantially equal to the

length of the shell, thus forming a single support, it will be understood that this length may be less, if found desirable, or, the support may be divided intermediate its 5 length to form a plurality of supports which are practically alined, an arrangement which is readily produced by forming the web of the blank with cut-out portions extending parallel to the top and bottom edges of the 10 web in Fig. 4, this being an obvious variation which may be employed if desired.

As will be seen, the arrangement will tend to produce a shell having a width greater than the length of the cigars or cigarettes, a 15 condition which, under ordinary forms of slide boxes, would permit a cigar or cigarette to cant and fall to the bottom of the slide when the major portion of the contents have been removed. However, since the 20 support acts to divide the slide into compartments each having a width less than the length of the cigar or cigarette, it will be clear that such shifting movements of the cigarette are limited so as to prevent the 25 cigar or cigarette from reaching a position extending substantially parallel with the bottom of the slide.

While I have herein shown and described one or more ways in which the invention 30 may be carried out, it will be readily understood that variations and modifications therein may be required or desired to meet the exigencies of use, and I desire to be understood as reserving the right to make any 35 and all such changes and modifications in so far as the same may fall within the spirit and scope of the invention as expressed in the accompanying claims:

Having thus described my invention, what 40 I claim as new, is:—

1. In slide boxes, a shell, and a slide therefor having opposing panels connected at one end and between which the contents are received, said slide including a wall structure 45 formed as a double wall to divide the slide into compartments and having a depth substantially equal to the depth of the slide and adapted to form a support for the span faces of the shell against inward collapsing.

2. In slide boxes, a shell, and a slide therefor having opposing panels connected at one end and between which the contents are received, said slide including a wall structure formed as a double wall to divide the slide 55 into compartments and having a depth substantially equal to the depth of the slide and adapted to form a support for the span faces of the shell against inward collapsing, said wall structure having a length substantially equal to the length of the shell.

3. In slide boxes, a shell, and a slide therefor having opposing panels connected at one end and between which the contents are re-

ceived, said slide including a wall structure formed as a double wall and adapted to divide the slide into commodity-receiving compartments and form a support for the span faces of the shell against inward collapse, each panel having an opposing panel structure and a closing flap individual to itself. 65 70

4. In slide boxes, a shell, and a slide therefor having opposing panels connected at one end and between which the contents are received, said slide including a web portion formed integral with and folded to produce 75 a wall structure of double wall type dividing the slide into compartments and adapted to form a support for the span faces of the shell against inward collapsing, said web portion being of a length less than the total 80 length of the connected opposing panels.

5. In slide boxes, a shell, and a slide therefor having opposing panels connected at one end and between which the contents are received, said slide including a bellows-fold 85 structure formed as a double wall and extending parallel with the side walls of the slide and adapted to form slide compartments, said structure having a depth substantially equal to the depth of the slide and 90 adapted to form a support for the span faces of the shell against inward collapsing, said bellows fold structure being of a length less than the total length of the connected opposing panels. 95

6. In slide boxes, a shell, and a slide therefor, said slide being formed from a blank having slide-forming portions each embodying opposing panels and an integral slide bottom, said portions being spaced apart and 100 connected by a web having a length not greater than the length of one of the panels and foldable to produce a compartment-forming wall structure of the double wall type extending in the direction of length 105 of the shell, the folded web serving to place similar panels of the slide forming portions in juxtaposition and to form a support for the span faces of the shell against inward collapsing. 110

7. A foldable blank adapted to produce a slide for slide boxes, said blank having a plurality of slide-forming elements each foldable to produce a slide formation embodying opposing panels and an integral slide bottom, similar panels of the slide formations being spaced apart and connected by a web structure having its length not greater than the length of one of the panels and having its direction of length extending parallel 115 with the similar direction of the connected panels and foldable to bring the connected panels into juxtaposition and produce a wall structure dividing the slide into compartments arranged side by side. 120

8. In slide boxes, a shell and a slide there-

for having a plurality of sets of opposed panels connected at one end and between which the contents are received, a panel of one set being connected to a similar panel 5 of another set to produce a double wall structure therebetween having a depth sub-

stantially equal to the depth of the slide, the remaining panels of the sets being free from such connection.

In testimony whereof I have hereunto set 10 my hand.

GEORGE M. WILLIAMS.
